CURTAIN AND SHADE FIXTURE

Bernhardt F. Klinzmann, Waterbury, Conn.

Application January 26, 1934, Serial No. 708,337

8 Claims. (Cl. 156—24)

This invention relates to window curtain and shade fixtures, and more particularly to an adjustable fixture adapted to support various sizes of shades, curtains, and over-draperies.

One object of this invention is to provide a device of the above nature having a base which may be permanently attached to a window frame, and which is slotted to detachably receive a plurality of flat projecting brackets which may be selectively moved to various horizontal positions upon said base.

A further object is to provide a fixture of the above nature in which the detachable supporting brackets are provided with positive locking means adapted to engage with edges of the slots in the base plate to prevent the brackets from becoming accidentally detached due to the weight of the shade or curtains.

A further object is to provide a fixture of the above nature in which the base is provided with an inclined resilient slotted flange for cooperating with cam engaging sections on the brackets, whereby said brackets may be readily removed and readjusted whenever desired.

A further object is to provide a fixture of this nature which will be simple in construction, inexpensive to manufacture, easy to install and manipulate, compact, ornamental in appearance, and very efficient and durable in use.

With these and other objects in view there has been illustrated on the accompanying drawing, one form in which the invention may be conveniently embodied in practice.

In the drawing:

Fig. 1 represents a perspective view of one of the curtain and shade fixtures as applied to a window frame, showing one shade roller bracket and two curtain brackets, and two associated curtain rods in assembled position.

Fig. 2 is a top plan view of the same with the curtain rods removed.

Fig. 3 is a left-hand end view of the same.

Fig. 4 is a transverse sectional view on a slightly enlarged scale of the base plate taken along the line 4—4 of Fig. 2.

Fig. 5 is a perspective view on a considerably enlarged scale of one of the curtain supporting brackets.

Referring now to the drawing in which like reference numerals denote corresponding parts throughout the several views, the numeral 10 indicates an elongated channel-shaped base plate or bracket holding frame preferably formed from sheet metal, and adapted to be permanently at-

tached to the upper right-hand corner of a window frame 11 by means of wood screws 12, as shown in Fig. 1. The base plate 10 is provided with a pair of upper and lower forwardly-extending longitudinal flanges 13 and 14, respectively.

The upper flange 13 is preferably bent at right-angle to the body 15 and terminates in an upwardly-extending arcuate bead 16. The horizontal section of the flange 13, is provided with a series of equally spaced slots 17 which are adapted to have interchangeable engagement with locking projections 18 formed on a pair of curtain rod brackets 19 and 20 and a shade roller bracket 21.

The lower flange 14 of the base plate 10, as best shown in Figs. 3 and 4, is inclined downwardly at an angle of substantially 45 degrees and terminates in a rearwardly-extending U-shaped bead 22. The flange 14 is provided with a series of elongated slots 23 located in direct vertical alignment with the slots 17 in the upper flange 13. The slots 23 are considerably longer than the slots 17 and extend from the junction line of said flange 14 and the body 15 to the outer end of the crown section of the bead 22, as shown in Fig. 4.

The slots 23 serve to receive cam-shaped lobes 24 formed on the brackets 19, 20 and 21 at the corners opposite from the locking projections 18. The inclined elongated slots 23 afford considerable resistance to lateral play or motion on the part of the brackets 19, 20 and 21 located therein.

Each curtain rod bracket 19, 20 is made from a flat metal stamping and includes a substantially rectangular body section 25 upon which the open inturned ends 26, 27 of the curtain rods 28, 29 are detachably engaged. The rods 28, 29 are of the conventional type and have the usual apertures 30 adapted to engage a pair of arcuate nips 31, 32 formed on the side longitudinal edges of the brackets 19, 20 by a snap-locking action.

A pair of intermediate abutment shoulders 33 and 34 are also provided on the opposite edges of the brackets 19 and 20 to form stops for the inturned ends 26 and 27 of the rods 28 and 29, when the latter are slipped into position upon said brackets 19 and 20.

The outer ends of the shade roller brackets 21 are provided with central apertures 35 to receive the usual pivot pins provided on the ends of the conventional shade roller, not shown.

While the drawing illustrates the appearance of the right-hand fixture, it will be understood that the left-hand fixture is identical therewith in all respects except that the brackets 19, 20

and 21 will be oppositely arranged upon the left-hand base plate 10.

Operation

- 5 In the use of this invention, the base plates 10 will first be fastened to the upper right and left-hand corners of the window frame 11. The shade roller supports 21 will then be inserted in the desired alined slots 17 and 23 according to 10 the length of the particular shade roller to be hung thereupon.

The brackets 19 and 20 will next be attached to the base plates 10 outside of the brackets 21.

- In assembling the bracket (19, 20, 21) to the 15 plate 10, the locking projection 18 will first be positioned in the desired slot 17 in the upper flange 13, and the bracket will then be forced downwardly to cause the cam lobe 24 to forcibly slip past the outer end 36 of the slot 23 until 20 the reentrant arcuate slot 37 formed adjacent the lobe 24 (see Fig. 5) engages the end 36 of said slot 37, as shown by the dotted lines in Fig. 4. A snap-locking engagement between said bracket and said plate 10 will thus be effected.
- 25 In order to release the supporting bracket (19, 20, 21) from the base plate 10, it will only be necessary for the operator to manually press downwardly on the U-shaped bead 22 with one hand, and pull upwardly with the other hand 30 upon the outer end of said bracket.

While there has been disclosed in this specification one form in which the invention may be embodied, it is to be understood that this form is shown for the purpose of illustration only, and 35 that the invention is not to be limited to the specific disclosure but may be modified and embodied in various other forms without departing from its spirit. In short, the invention includes all the modifications and embodiments coming with- 40 in the scope of the following claims.

Having thus fully described the invention, what is claimed as new, and for which it is desired to secure Letters Patent, is:

1. In a curtain fixture, a base plate comprising 45 a body portion, upper and lower forwardly-extending flanges connected to said base plate and having vertically alined slots therein for supporting a bracket member having interlocking engagement with said slots.

50 2. In a curtain fixture, a base plate comprising a body portion and upper and lower forwardly-extending parallel flanges, each flange having a plurality of spaced slots therein, the slots in said respective flanges being in vertical alinement 55 for supporting a bracket member fitted into said slots with a detachable snap-locking engagement.

3. In a combination curtain and shade supporting fixture, a base plate having longitudinal 60 upper and lower flanges extending forwardly therefrom, said flanges having a plurality of spaced longitudinal slots provided therein in vertical alinement with respect to each other for supporting a plurality of bracket members having 65 detachable snap-locking engagement within alined slots in said flanges for supporting the conventional type of curtain rods and shade rollers thereupon.

70 4. In a combination curtain and shade supporting fixture, a base plate for attachment to a window frame, said plate being bent longitudinally to form upper and lower forwardly-extending parallel flanges, the upper flange being

substantially horizontal, and the lower flange inclined at an angle of substantially forty-five degrees, said flanges being provided with a plurality of spaced slots located in vertical alinement with each other for supporting a plurality of 80 bracket members having means for selective detachable snap-locking engagement within aligned pairs of said slots for supporting the conventional type of U-shaped curtain rods thereupon.

5. In a combination curtain and shade sup- 85 porting fixture, a base plate having means for at-

achment to a window frame, said plate being bent longitudinally to form upper and lower forwardly-extending parallel flanges, the upper flange being horizontal and the lower flange being downwardly inclined from said body, said flanges being provided with a plurality of spaced slots in vertical alinement with respect to each other for supporting a plurality of supporting curtain brackets, each having a projecting locking lug formed at 90 one corner thereof for interlocking selective engagement in one of the slots in said upper flange, each bracket also having a cam-shaped lobe on its opposite side for snap-locking engagement in one of the slots in said inclined flange.

6. In a combination curtain and shade sup- 95 porting fixture, a base plate having means for at-

achment to a window frame, said plate being bent longitudinally to form upper and lower forwardly-extending parallel flanges, the upper 100 flange being horizontal and the lower flange being

downwardly inclined from said body, said flanges being provided with a plurality of spaced slots in vertical alinement with respect to each other for supporting a plurality of supporting curtain 105 brackets, each having a projecting locking lug formed at one corner thereof for interlocking selective engagement in one of the slots in said upper flange, each bracket also having a cam-

110 shaped lobe on its opposite side for snap-locking engagement in one of the slots in said inclined flange, the lobes of said bracket projecting a sub-

stantial distance through the lower slot to prevent lateral twisting of said brackets.

7. In a combination curtain and shade sup- 115 porting fixture, a base plate having longitudinal upper and lower flanges extending forwardly therefrom, said flanges having a plurality of spaced longitudinal slots provided therein in vertical alinement with respect to each other for sup-

120 porting a plurality of bracket members having detachable snap-locking engagement within the alined slots in said flanges for supporting the conventional type of curtain rods and shade rollers thereupon, said lower flange being re-

125 silient and being adapted, when manually de-

pressed, to release said bracket members from interlocking engagement.

8. In a combination curtain and shade sup- 130 porting fixture, a base plate having longitudinal upper and lower flanges extending forwardly therefrom, said flanges having a plurality of spaced longitudinal slots provided therein in vertical alinement with respect to each other for sup-

135 porting a plurality of bracket members having detachable snap-locking engagement within the alined slots in said flanges for supporting the conventional type of curtain rods and shade rollers thereupon, said brackets having on op-

140 posite side edges a pair of shoulders serving to form abutments for the inturned ends of the curtain rods.

BERNHARDT F. KLINZMANN.
